CALCULATING MACHINE

Daniel Broido, Cockfosters, near Barnet,
EnglandApplication December 9, 1944, Serial No. 567,347
In Great Britain December 10, 1943

5 Claims. (Cl. 235—61)

1

This invention relates to calculating machines for non-uniform numerical systems comprising interrelated sets of units (such as £ s d) of the type based on repeated addition.

In decimal calculating machines of this type the relative position of the result register and of the value-entering means is normally changed by displacing a carriage transversely to the machine. This carriage shift is utilised to increase the set-up values by decimal multiples.

In the specification to my Patent No. 2,408,134 there is described a calculating machine for non-uniform numerical systems, wherein the carriage shift is used similarly to decimal machines to increase, or to decrease, the set-up amount by decimal multiples.

The object of the present invention is to provide a calculating machine for non-uniform numerical systems comprising interrelated sets of units (such as £ s d), wherein not only non-uniform amounts may be multiplied by decimal amounts, but conversely decimal amounts may be multiplied by non-decimal amounts, without any decimalisation.

A further object of the invention is to provide a calculating machine wherein non-uniform amounts may be divided by decimal amounts without any decimalisation.

Another object of the invention is to provide a calculating machine indicating correctly multipliers and quotients in decimal or non-decimal systems, as the case may be, without the error involved in decimalisation or re-decimalisation of non-decimal amounts.

Yet another object of the invention is to provide a calculating machine wherein the carriage shift is utilised to increase, or to decrease the set-up amount by decimal multiples or by non-decimal multiples as desired.

Yet a further object is to provide a calculating machine with two independent carriage shifts, one shift being used for decimal multipliers or quotients and the other shift being used for non-decimal multipliers or quotients.

Another object is to provide a calculating machine having a revolution register which indicates each revolution of the main operating shaft in any position of the carriage, each revolution resulting in addition or subtraction of a decimal or a non-decimal multiple of the set-up amount, according to the position of the carriage.

Further objects of the invention will become apparent as the description proceeds.

With these objects in view, a calculating machine for non-uniform numerical systems comprising interrelated sets of units made according to the invention comprises a set-up mechanism for the first factor entering into a calculation, a conversion mechanism having physical representations of all set-up values multiplied

2

by unit values of the denominations of the interrelated sets of units, said multiples being expressed in the interrelated sets of units, means for selecting those of said representations which correspond to denominations of the interrelated sets of units comprising the second factor entering into a calculation, a feeler mechanism adapted to sense said representations, a products register, and means for entering the sensed values into the products register repeatedly in accordance with the denominational values of the various sets of units of the non-uniform factor.

The invention further comprehends a calculating machine suitable both for non-uniform and decimal multipliers and quotients comprising a set-up mechanism for the non-uniform factor, a conversion mechanism having physical representations of decimal multiples of all set-up values and also physical representations of non-decimal multiples of all set-up values of the highest set of units multiplied by unit values of the denominations of the lower sets of units, said multiples being expressed in the interrelated sets of units, means for selecting said representations according to the denominations of the second factor entering into a calculation, a feeler mechanism adapted to sense said representations, a products register, and means for entering the sensed values into the products register repeatedly in accordance with denominational values of the second factor.

In the accompanying drawings which illustrate a machine made according to the present invention:

35 Figure 1 is a conversion table,
Figures 2, 3, 4, 5, and 6 show the selector plates of the top bank, second bank, third bank, fourth bank, and bottom bank, respectively;

40 Figures 7 and 8 illustrate diagrammatically the arrangement of the selector plates used in the machine,

Figures 9, 9A together represent a vertical section on line IX—IX of Figures 10, 10A; (also indicated in 13 and 14),

45 Figures 10, 10A together represent a section on line X—X of Figures 9 and 9A,

Figure 16 is a section approximately on line XVI—XVI of Figures 9, 9A,

Figure 17 is a fragmentary view in the direction of arrow XVII in Figure 18,

60

Figure 18 is a view of the machine, on a reduced scale, taken in the direction of arrow XVIII in Figures 9, 9A.

Figure 19 shows in detail one of the selector plates used in the machine, and

Figure 20 shows another selector plate used in the machine.

General arrangement

The machine illustrated in the drawings comprises, broadly, a shiftable set-up and conversion mechanism, a products register, a feeler mechanism adapted to transfer the set-up values to the products register, a revolution register for indicating the number of said transfers, and driving means and other associated devices. As shown in Figures 9, 9A, 10 and 10A, the various mechanisms are mounted on a base plate 1 in the frame structure 2, 3 and are protected by a cover 4.

Set-up and conversion mechanism

As shown in Figures 9, 9A, 10, and 18, the set-up mechanism comprises ten setting levers 5, of which five levers are reserved for the pounds denominations (designated L^{10⁴}—L¹), two for the shillings (tens S¹⁰ and units S¹), one for pence (D), and two levers for tenths and hundredths of a penny, respectively (D^{10⁻¹}, D^{10⁻²}). All setting levers 5, Fig. 9, are rockably mounted on a shaft 6 fixedly supported in side plates 7, 8, Fig. 10, fixed to cross bars 9 (Figure 9) (hereafter referred to as the "carriage"). Forward extensions of levers 5 protrude through slots in carriage cover 10 so as to be rocked into alignment with numerals arranged along the respective slots to indicate the set-up values. Each lever 5 has serrations 11 co-operating with detents 12 rockable on a rod 13 secured in carriage plates 7, 8. Springs 14 hold the detents 12 in engagement with serrations 11, guide plates 15 serving to prevent the detents from slipping off the serrations.

Setting levers 5 serve to bring into working position selector plates 16, one of which is provided for each numeral marked on carriage cover 10 adjacent to the respective slots. These selector plates, which constitute the conversion mechanism and will be fully described hereafter, are arranged in five banks clearly shown in Figures 9, 9A. The top bank comprises L^{10³} and D selector plates 16 (shown in detail in Figure 2) which are rockably supported on shaft 6 by the respective setting levers 5 and bails 17, as shown in Figure 10. The four lower banks comprise selector plates L¹⁰ and D^{10⁻¹} (shown in detail in Figure 3) (second bank from top); L¹ and D^{10⁻²} (shown in detail in Figure 4) (third bank); L^{10²} and S¹ (shown in detail in Figure 5) (fourth bank); and L^{10⁴} and S¹⁰ (shown in detail in Figure 6) (bottom bank). Selector plates 16 of the lower banks are mounted in bails 18 rockable on respective shafts 19 secured in carriage plates 7, 8. The bails 18 supporting each set of plates 16 are connected by a link 20 to the respective setting lever 5 mounted on shaft 6 between the levers 5 and bails 17 supporting the selector plates 16 (L^{10³} and D) of the top bank, as shown in Figure 10. Selector plates 16 co-act with five banks of sensing pins 21 mounted for sliding movement opposite the respective banks of selector plates. By aligning the setting levers 5 supporting the selector plates 16 of the top bank with certain numerals on carriage cover 10, the corresponding selector plates 16 are brought into

working position opposite the sensing pins 21 of the uppermost bank. Similarly, by aligning the setting levers 5 connected by links 20 to bails 18 supporting the selector plates 16 of the lower banks with certain numerals on carriage cover 10, the corresponding selector plates 16 are brought into working position opposite the sensing pins 21 of the respective banks.

A restoring bar 22 pivoted on shaft 6 has a handle 23 protruding through a slot in carriage cover 10. When handle 23 is lifted upwards, bar 22 rotates around shaft 6 and restores all setting levers 5 into the initial position.

Carriage 9 is mounted for transverse movements on rollers 24 running in rails 25, 26. A spring 27 mounted in barrel 28 runs over pulley 29 (Figure 10) and is secured to carriage plate 8, so as to pull the carriage to the left. An escapement pawl 30 pivoted at 31 (Fig. 11) on carriage 9 co-acts with a rack 32 fixed to base plate 1. A shift lever 33 (Fig. 9) pivoted at 34 in carriage 9 protrudes forwardly through a slot in carriage cover 10 and has a knob 35; spring 36 tends to rock the lever 33 clockwise as viewed in Figure 9. As shown in Figure 11, the rear end of lever 33 engages a slot in pawl 30, thus rocking it anti-clockwise so that a nose 37 formed on pawl 30 engages the teeth of rack 32. A second escapement pawl 38 pivoted at 39 is biased by a spring 40 on to an abutment 41 formed on pawl 30, so that this second pawl 38 is normally clear of the teeth of rack 32. When knob 35, Fig. 9, is depressed, the rear end of lever 33 swings the pawl 30 clockwise as viewed in Figure 11, thus disengaging the nose 37 from rack 32 and causing the second pawl 38 to rock downwards. The carriage is then shifted by spring 27 approximately half a step to the left, whereupon the second pawl 38 engages the rack 32. When knob 35 is released, lever 33 and pawls 30 and 38 are restored by springs 36 and 40, and nose of pawl 38 disengages rack 32, whereupon the carriage is again shifted for approximately half a step until nose 37 re-engages rack 32. Thus, the total movement of the carriage 9 upon each depression of knob 35 equals the pitch of rack 32. The carriage is arranged to move in equal steps a maximum of seven steps to the left from the initial position, and four steps to the right thereof. Each of these eleven steps of the carriage is equal to the distance between two adjacent register wheels of the pounds set of units. In addition the carriage may move four more steps to the right, these four additional steps being unequal to the said distance as will be fully explained hereafter.

As shown in Figure 18, the various positions of the carriage are indicated by a pointer 42 formed on carriage cover 10, which pointer co-acts with numerals +1 to +7 on machine cover 4 to indicate positions to the left from the initial position designated 0, and with indications -1 to -4 and S¹⁰, S¹, D, D^{10⁻²} to indicate the shift to the right.

A special arrangement is provided for the four last positions of the carriage at the right-hand side of the machine. This consists of four stop plates 43—46 shown in Figs. 11 and 12. Plate 43 is reserved for the carriage position S¹⁰ associated with tens of shillings as will be fully described hereafter, plate 44 is reserved for units of shillings S¹, and plates 45—46 are reserved for pence D and eightths of a penny D^{10⁻²} respectively. Plates 43—46 are pivoted on a pin 47 in brackets 48 secured to base plate 1 and are held in their normal position by springs 49 against a stop 50. Each stop plate 43—46 is formed with a tooth 51

and a hump 52. Fixed to the carriage 9 adjacent to the escapement pawls is a plate 53 adapted to engage any one tooth 51 and to stop the carriage 9 in the respective position. The co-operation of plate 53 with tooth 51 on the last stop plate 46 reserved for D/8 is shown in dash-and-dot lines on Figs. 11 and 12. To allow carriage 9 to travel to the left, knob 35, Fig. 9, is depressed, the rear end of lever 33 rocks pawl 30, Fig. 11, so that abutment 41 is depressed as already described. As this abutment 41 is above hump 52 on plate 46, this particular plate will be depressed and tooth 51 will be disengaged from plate 53, thus allowing the carriage to travel to the left until stopped by tooth 51 on the next stop plate 45. Thus on each depression of the knob 35, Fig. 9, the carriage 9 is allowed to travel to the left an amount determined by the distance between the teeth 51 on stop plates 43—46.

When the carriage is located in position S10, the plate 53 engages tooth 51 on stop plate 43. When the shift lever 33 is depressed the carriage will shift to the left until the second escapement pawl 38 engages the face of rack 32. When the lever 33 is released, pawl 38 disengages the rack 32 and nose 37 on pawl 30 engages the first tooth on rack 32, as shown in Fig. 11. On further depression of shift lever 33, the carriage shifts to the left in equal steps as already described.

Return movement of carriage 9 is effected by knobs 54, Figure 9, on a hand wheel 55 journaled in the carriage. Hand wheel 55 is fixed to a gear 56 secured to one of rollers 24. Gear 56 meshes with a rack 57 formed on front rail 25. By turning the hand wheel 55 clockwise (as viewed from the front of the machine), the carriage 9 is shifted to the right.

The carriage shift is utilized to multiply the set-up values by decimal multiples, i. e., by 10, 100, 1000, and so forth when shifted into position +1, +2, and so forth, or by 0.1, 0.01, and so forth when shifted into position -1, -2, and so forth, or by non-decimal multiples 10/-, 1/-, 1d., or 1/6d. when shifted into position S10, S1, D, or D/8, respectively. This arrangement of the set-up mechanism provides, in the present embodiment, for a capacity up to 99,999,999.9999 or

£99,999,999:19:117d.

for the multiplier, and up to £99,999:19:11.99d. or 99,999 for the multiplicand. The product may comprise thirteen pounds denominations, two shillings denominations, pence denomination, and six denominations of decimal fractions of a penny. A sensing pin 21 is provided for each bank of selector plates 16 for each of these twenty-two possible result denominations. The transverse distance between the sensing pins 21, as may be seen from Figures 7 and 8, is the same between the pins associated with L10¹¹—L1 and D10⁻¹—D10⁻⁶ denominations, namely equal to the carriage shift in decimal positions, but it is different to the distance between sensing pins L1, S1, D1, and D10⁻¹. The importance of this arrangement will become apparent as the description proceeds.

Selector plates 16, except those reserved for the zero values, are notched so as to represent the converted decimal or non-decimal multiples of the respective set-up values. The manner in which the decimal multiples are represented by notches has been fully described in the specification to my Patent No. 2,408,134, and it will be only briefly described in the present specification. The arrangement of the notches will be evident

from an inspection of Figures 7, 8, 19, and 20. The general arrangement of notches in two representative plates 16, namely those associated with "nine pounds" (£9) and "six pence" (6d.), is shown in Figures 19, 20, respectively. In these figures each notch is identified as to its associated numerical value (line a of the table arranged above each plate), as to its denominational significance (line b), and as to the ordinal position of the carriage in which this notch becomes effective (line c), as will be fully described hereafter. Thus, in Figure 19 the extreme left-hand notch represents the value "four" of the pounds denomination; it will become effective in the S10 position of the carriage. In Figure 20, the deepest notch represents "6" of the decimalsof-a-penny denominations; it will be effective in any carriage position from -1 to -4.

Fig. 7 illustrates the carriage shift to the left. It shows two selector plates 16 of the top bank, namely those associated with 700 (or £700), and 7d., designated respectively L10²(7), and D(7). Sensing pins 21 are represented by thick vertical lines designates L10¹¹—D10⁻¹ along the top edge of the drawing. The transverse positions of the carriage are designated by numerals 0 to +7 along the right-hand edge of the drawing. Selector plates 16 in line with each of these numerals are shown in their actual positions relatively to the sensing pins 21 in the respective transverse positions of the carriage.

Considering first the pence selector plate D(7), it will be seen that in the initial position 0 only one sensing pin 21 will be aligned with a notch in the plate, namely the D pin; the depth of this particular notch is such as to represent "7," i. e., it is seven "unit steps" deep, as indicated by the numeral 7 adjacent to this notch. The sensing pins 21 are arranged to move into the notches 40 and to transfer the values associated with each notch to the corresponding numeral wheel of the products register, as will be fully described hereafter. Evidently the amount of movement of each sensing pin, viz., the amount transferred to the 45 respective register wheel, is determined by the depth of the respective notch. If a sensing pin does not encounter a notch, i. e., is stopped by the edge of the selector plate, it does not move appreciably, and the associated register wheel is 50 not operated at all. In the present case, only the D pin will enter a notch, and thus it will transfer the value "7" associated with this notch to the pence wheel of the products register.

The tens of shillings values of the multiples are 55 arranged separately from other values on bars 58, one of which is fixed to each plate 16 along its edge just above it, as clearly shown in Fig. 9. Accordingly, the S10 sensing pin 21 is arranged somewhat higher than all other sensing pins. In 60 Figures 7, 8 the bars 58 are shown diagrammatically below the respective selector plates 16. Since the digit of tens of shillings is either 0 or 1, bars 58 are cut away to represent 10/-; the S10 feeler mechanism is arranged to move not more than one step, as will be described hereafter. As indicated in Fig. 7, bars 58 extend from the setting lever 5 to the bail 17, the gap between bars 58 on L10²(7) and D(7) plates 16 being filled by bail 17 and lever 5, as shown in dotted lines. 65 Thus, in position 0 the S10 sensing pin 21 registers 0.

When the D(7) selector plate is shifted one step to the left in position +1, sensing pins S1 and D will be aligned with notches representing 75 "5" and "10" respectively; consequently, the

amount $5/10d = 7d \times 10$ will be entered into the register. When the selector plate is in position $+2$, the L_1 , S_1 , and D pins will be aligned with notches 2 , 8 , and 4 respectively, and the S_{10} pin is aligned with a gap in bar 58 as designated by 4 ; consequently, the amount

$$£2:18:4d = 7d \times 100$$

will be registered. Similarly, when the selector plate is in position $+3$, the amount

$$£29:3:4d = 7d \times 1000$$

will be registered by pins L_{10} , L_1 , S_1 and D entering notches 2 , 9 , 3 , and 4 , respectively. When the plate is in position $+4$, the amount

$$£291:13:4d = 7d \times 10,000$$

will be registered by pins L_{10}^2 , L_{10} , L_1 , S_1 , and D in co-operation with notches 2 , 9 , 1 , 3 , 4 respectively, and pin S_{10} in co-operation with a gap in bar 58 . When the plate is shifted into positions $+5$, $+6$ or $+7$, the respective pins are operated so as to register $£2,916:13:4d = 7d \times 100,000$

$$£29,166:13:4d = 7d \times 1,000,000$$

and $£291,666:13:4d = 7d \times 10,000,000$, respectively. It will now be seen why the different spacing between the sensing pins of various denominations is necessary: the notches representing pence values must not be aligned with pins 21 associated with shillings or pounds register wheels, and vice-versa.

An inspection of selector plate $L_{10}^2(7)$ in Figures 7, 8, and of selector plate $L_1(9)$ in Figure 19 shows that notches in the plate are arranged in two groups, the right-hand group representing the decimal multiples and the left-hand group representing the non-decimal multiples. Locking means indicated by horizontal lines 59 , Figures 7 and 8, more fully described hereafter, are provided to render the non-decimal group of notches inoperative in the decimal positions of the carriage, and vice-versa.

Considering now the selector plate $L_{10}^2(7)$, in the initial position 0 only one notch designated 7 , which is seven steps deep, is aligned with a sensing pin unaffected by the locking device 59 , namely that of the L_{10}^2 denomination. Consequently, the amount $£700$ will be registered. When this plate is shifted to the left, this same notch 7 will be aligned with pins 21 of the higher pounds denominations L_{10}^3 — L_{10}^9 , since, as already mentioned, the transverse distance between adjacent sensing pins associated with pounds register wheels is equal to the transverse step of the carriage in its decimal positions; thus $£7,000$, $£70,000$ and so forth will be registered when the plate is in position $+1$, $+2$, $+3$, and so forth, respectively. Considering now the shift to the right illustrated in Fig. 8 upper part, in position -1 this notch, being aligned with the L_{10} pin, will cause it to register $£70$; in position -2 , pin L_1 will register $£7$. When the plate is in position -3 , this notch 7 is not aligned with any pin 21 ; instead, another notch 4 , which is four steps deep, will be aligned with the S_1 sensing pin, and a gap in bar 58 will be aligned with pin S_{10} , which thus enter into the register $14/- = £700 \times 0.001$. Finally, in position -4 notches 1 , 4 , and 8 will be aligned with pins S_1 , D and D_{10}^{-1} respectively, which will register $1/4.8d = £700 \times 0.0001$. As to the $D(7)$ selector plate, the notch 7 herein registers, in position -1 to -4 , $0.7d$, $0.07d$, $0.007d$, and $0.0007d$, respectively.

It will be noted that if a notch represents a

digit of a decimal set of units (pounds or decimals of a penny), this notch may be aligned, due to carriage shift, with sensing pins of several denominations of this set of units, but if a notch 5 represents a digit of a non-decimal denomination (tens of shillings, or units of shillings, or pence), this notch will be aligned only with the sensing pin of this particular denomination.

The lower part of Figure 8 illustrates the carriage shift into non-decimal positions, such as may occur during multiplication of a decimal amount by shillings or pence. The decimal multiplicand is set up on pounds selector plates; thus, to multiply $700 \times 10/-$, the $L_{10}^2(7)$ selector plate 10 is brought into the working position and the carriage is shifted into position S_{12} , as indicated at S_{10} in Fig. 8. In this non-decimal position, the decimal group of notches on the right is rendered inoperative by the locking device 59 . From the non-decimal notches on the left, those designated 3 and 5 are aligned with sensing pins L_{10}^3 and L_{10}^5 ; thus $£350 = 700 \times 10/-$ is registered. In position S_1 , these same notches are aligned with pins L_{10} and L_1 , respectively, thus registering $£35 = 700 \times 1/-$. In position D notches 2 , 3 , and 4 are aligned with pins L_1 , S_1 , D , respectively, and a gap in bar 58 is aligned with pin S_{10} ; thus, $£2:18:4d = 700 \times 1d$ is entered into the register. Finally, in position $D/3$ notches 7 , 3 , and 5 are aligned, respectively, with sensing pins S_1 , D , and D_{10}^{-1} , thus registering $7/3.5d = 700 \times \frac{1}{3}d$.

The converted values of all non-decimal multiples of the set-up decimal values within the capacity of the machine are shown in Figure 1. The values of decimal multiples of sterling set-up values will be found in Figures 1-3 of my above-mentioned Patent No. 2,408,134.

Selector plates 16 of the top bank, second bank, third bank, fourth bank, and bottom bank are shown in Figures 2, 3, 4, 5 and 6, respectively. In these figures, the numerals $0-9$ or $0-11$ designate the set-up values associated with respective selective plates 16 and bars 58 ; the dotted vertical lines approximately in the middle of the drawings indicate the position of the D sensing pin 21 related to the initial position of the carriage.

The capacity of the machine made according to the invention is not limited to that specified above. Both the number of carriage shifts (which determines the multiplier) and the number of denominational sets of selector plates (which determines the set-up factor, e.g. multiplicand) may be increased or decreased as desired. The notches in the selector plates may be arranged to suit not only the pounds sterling system of notation, but any other numerical system, for instance the avoirdupois system, Indian currency, and so forth.

Feeler mechanism

As already described, the notched selector plates 16 and bars 58 determine the amount of movement of sensing pins 21 during the working cycle of the machine. As shown in Figure 9A, sensing pins 21 co-act with five-pronged feelers 68 pivoted at 61 in gear sectors 62 rockable on a shaft 63 fixed in the supporting structure. Each gear sector 62 co-operates with a numeral wheel of the products register as will be described hereafter. Rockably mounted on shaft 63 adjacent to each gear sector 62 is a lever 64 which has a pin 65 engaging a slot in gear sector 62 (see also Figure 14); a spring 66 , Fig. 9A, connects each sector with its lever. A stronger spring 67 an-

chored in a spring bar 68 tends to swing each lever 64 anti-clockwise as viewed in Figure 9A, so that it abuts against a restoring bar 69. This bar is common to all levers 64; it extends across the machine and is at each end pivotally mounted on shaft 63, a spring 70 keeping a roller 71 journaled at each side of bar 69 in contact with a cam 72. During each revolution of cams 72 the levers 64 and gear sectors 62 are reciprocated five times.

A link 73 is pivoted at 74 to each feeler 60. The lower ends of links 73 are pivoted on a common rod 75 supported in a bar 76 rockable on shaft 63; a roller 77 journaled at either end of bar 76 is biased on to a cam 78 by a spring 79. Cams 78 are so shaped as to rock the feelers 60 prior to the first forward (anti-clockwise) movement of levers 64 and gear sectors 62 so that the upper prongs of feelers 60 are aligned with the upper bank of sensing pins 21, whereas the lower prongs are not aligned with their respective banks of pins 21; prior to the second forward movement feelers 60 are rocked so that the second prongs are aligned with the second bank of pins 21, and so forth; finally, prior to the fifth forward stroke of feelers 60 they are rocked by cams 78 so that their lowest prongs are aligned with the lowest bank of pins 21, the other prongs being out of alignment with their respective banks of sensing pins 21. Thus, during a complete revolution of cams 72, 78, the five banks of pins 21 are contacted in succession by feelers 60 and pushed forward into the notches of selector plates 16 and into gaps in bars 58. As the extent of movement of pins 21 is determined by the depth of notches they encounter, the amount of movement of feelers 60, gear sectors 62, and levers 64 is also determined by these notches in the selector plates; consequently, the amount of movement imparted by each gear sector 62 to the register wheel which it drives in a manner to be described hereafter is also determined by the numerical values represented by the respective notches or by gaps in bars 58, respectively.

Shaft 63, rod 75, and pivots 61, 74 form a parallelogram, so that prongs of feelers 60 are reciprocated along parallel and substantially straight lines. Guides 80 serve to ensure proper alignment of feelers 60 with sensing pins 21 slidably mounted in brackets 81 and biased towards the rear of the machine by springs 82.

The reason for the five-bank arrangement of selector plates 16 and sensing pins 21, and for the successive reading-out of these five banks by a five-step movement of feelers 60 and gear sectors 62 will be apparent after the following consideration. Assuming it is desired to multiply $99999 \times \frac{1}{8}d.$, all five sub-products: $90000 \times \frac{1}{8}d. = \frac{46}{17}d.$; $9000 \times \frac{1}{8}d. = \frac{4}{13}d.$; $900 \times \frac{1}{8}d. = \frac{9}{4}d.$; $90 \times \frac{1}{8}d. = 1.125d.$ and $9 \times \frac{1}{8}d. = 1.125d.$ contain pence values to be entered into the same register wheel D. Evidently, this cannot be done simultaneously; each sub-product must be registered separately, the whole operation to obtain the result $\frac{52}{17}d.$ being completed in five successive steps.

Prongs on feelers 60 are so shaped that when they are rocked into alignment with their respective sensing pins 21, the latter are pushed forward slightly until they encounter the edge of a selector plate 16, or bar 58, or just begin to enter a notch or gap therein, as the case may be. In the normal position none of the prongs on feelers 60 is aligned with pins 21, as shown in Fig. 9A, and pins 21 are slightly moved away from

plates 16 and bars 58 by their springs 82 so that a clearance herebetween enables the carriage 9 to be freely moved transversely of the sensing pins 21.

5 Gear sectors 62 have lower extensions 83, Fig. 9A, adapted to co-act with locking pawls 84 pivoted in a bar 85 fixed to base plate 1. Springs 86 bias the pawls 84 into engagement with extensions 83, thus locking the gear sectors 62 and 10 preventing their forward movement when released by cams 72 (see also Fig. 10A). Locking pawls 84 are controlled by a knock-out plate 87 fixed to carriage 9. The arrangement is such that when the carriage 9 is in any one of decimal 15 positions +7 to -4, the knock-out plate 87 rocks the respective pawls 84 to unlock those of gear sectors 62 which are aligned with the right-hand group of notches referred to in paragraph 2, page 13, that is with notches associated with decimal multiples, while those sectors 62 which are aligned with the left-hand group of notches, that is with notches associated with non-decimal 20 multiples, remain locked by their pawls 84. Conversely, when the carriage 9 is in any one non-decimal position S10, S1, D or D/8, the knock-out 25 plate 87 unlocks for operation gear sectors 62 aligned with notches associated with non-decimal multiples, and locks gear sectors aligned with notches associated with decimal multiples. The 30 position of the knock-out plate 87 relatively to pins 21 in each carriage position is indicated in Figures 7 and 8 diagrammatically by lines 59 drawn across dotted lines descending from those sensing pins 21 which are rendered inoperative 35 by the knock-out plate 87, that is those pins 21 with which the knock-out plate 87 is not in alignment.

Products register

40 Each gear sector 62 drives a denominational unit of the products register as shown in Figure 9A. As all these units are substantially alike, only a few of them are shown in Figure 14.

Gear sectors 62 mesh with small pinions 88 rotatable on shaft 89 supported in the frame structure 2, 3. Rigidly fixed to each pinion 88 45 is a disc 90 and a washer 91, and a gear 92 is rotatably mounted on disc 90. As clearly shown in Figure 15, gears 92 have internal ratchet teeth 93; a driving spring 94 fixed to the hub of each disc 90 engages the ratchet teeth 93. During the forward stroke of gear sectors 62 the gears 92 remain stationary, as the driving springs 94 rotate within the ratchets 93 (clockwise as viewed in Figure 15) without engaging the ratchet teeth. 50 During the return stroke of sectors 62 the driving springs 94 engage the ratchet teeth 93 and thus rotate the gears 92. Gears 92 mesh with idler gears 95 (Figures 14 and 9A) rotatable on shaft 96 supported at each end in a plate 97 (Figures 9A and 16). A second series of idler gears 98, Fig. 9A, is rotatably mounted on a shaft 99 also supported in plates 97. Those plates 97 are pivoted at 100 in the supporting structure of the machine; they can be rocked around their pivots 100 (by means to be described hereafter) in order to drive register gears 101 positively or negatively as desired. When the machine is conditioned for addition or multiplication, the idlers 95, 98 are in the position shown in Figure 9A; idlers 98 are not in mesh with register gears 101 which are driven directly by idlers 95 "positively," viz. anti-clockwise. When the machine is conditioned for subtraction or division, idlers 95, 98 are rocked around pivots 100 so that idlers 95 are not in mesh 60 with register gears 101 but idlers 98 are; conse- 70 quently, the idlers 98 drive the register gears 101 negatively.

quently, gears 101 are driven "negatively," viz. clockwise as viewed in Figure 9A.

Register gears 101 are rotatable on shaft 102 journalled in the supporting structure. Rigidly fixed to each gear 101 is a locating gear 103 (Figure 14), a numeral wheel 104, and a carry pinion 105. The numerals on wheels 104 are visible through apertures 106 in the machine cover 4 (Figures 9A and 18).

Locating gears 103 co-operate with detents 107 (Figure 9A) rockable on a rod 108 and biased by springs 109 housed in a spring bar 110. All locating gears 103 have ten teeth except that of the pence denomination D which has twelve teeth according to 0-11 pence. In order to produce a $\frac{1}{12}$ step of the D numeral wheel 104 as compared with the $\frac{1}{10}$ step of all other wheels 104, those notches in the selector bars 16 which are reserved for cooperation with the D feeler 62 are made correspondingly shallower, each unit step of these notches being $\frac{1}{12}$ of the unit step of all other notches.

Carry pinions 105 each have one tooth except the S10 pinion which has five teeth, since the S10 numeral wheel 104 must carry five times during each complete revolution. Pinions 105 co-act with carry pawls 111 which, like detents 107, are rockable on rod 108 and are biased by springs similar to detent springs 109. The upper parts of pawls 111 is shaped like detents 107, but they are bent sideways to co-operate with the gear sector of the next higher denomination. Each carry pawl 111 has an arm 112 (Figure 9A) co-acting with an abutment 113 formed on gear sector 62 of the next higher denomination. A second arm 114 on pawl 111 co-acts with a latch 115 rockable on a rod 116 and biased by a spring 117 housed in spring bar 68.

When a carry has to be effected, carry pinion 105 causes carry pawl 111 to swing out clockwise as viewed in Figure 9A, so that abutment 113 on gear sector 62 of the next higher denomination is no more supported by arm 112; this sector 62 swings under the influence of its spring 66 until its abutment 113 encounters a shoulder 118 formed on arm 112 as to allow for one-step movement of gear sector 62, which thus drives the associated numeral wheel 104 one step so as to effect the carry. The length of slots in gear sectors 62 embracing pins 65 in levers 64 is also chosen accordingly to allow for one-step movement of gear sectors 62 independently of levers 64.

When carry pawl 111 swings clockwise to effect the carry, latch 115 is also rocked clockwise by its spring 117 so as to lock the pawl 111 in the "carry" position. Thus, if a carry has to be effected while the gear sector 62 of the next higher denomination is being moved by the restoring bar 69, the carry pawl 111 will remain in the "carry" position until after the sector 62 returns to its initial position. As the abutment 113 on sector 62 will not encounter the end of arm 112, the sector will continue to move clockwise until its abutment 113 runs up against shoulder 118, thus effecting the carry. At the beginning of the next forward stroke of gear sectors 62, a restoring bar 119 pivoted at each end at 120 restores all previously operated latches 115. It has rollers 121 co-acting with cams 72; it is restored by springs 122.

It will be understood that whenever cams 72 cause levers 64 to swing forward (anti-clockwise as viewed in Figure 9A), levers 64 restore those gear sectors 62 which have previously effected the carry operation into position shown in Figure

9A, whereupon sectors 62 and feelers 60 either continue their forward stroke or remain stationary, according to whether the corresponding sensing pins 21 encounter notches in selector plates 16 or gaps in bars 58, or not.

Numeral wheels 104 are zeroised in a conventional manner by means of a spring-loaded comb bar 123 (Figure 14) slideable in a key-way in shaft 102. Lugs 124 on bar 123 co-operate with studs 125 formed on register gears 101. The zeroising operation is effected by turning a clearing handle 126 (Figure 18) fast on shaft 102; a cam-like recess in one of the bearings (not shown) of the register shaft 102 causes the comb-bar 123 to shift slightly to the left as viewed in Figure 14, whereupon lugs 124 pick up studs 125 and restore the numeral wheels 104 to the initial position. Comb-bar 123 is then restored by its spring (not shown) into the recess in the bearing. The products register comprises one more numeral wheel L10¹² (Figure 18) than is actually required for the capacity of the machine. This additional numeral wheel serves to store the carries from the L10¹¹ wheel. It is operated by a gear sector 62 and lever 64 which do not have a feeler 60.

Revolution register

As shown in Figures 9 and 13, the revolution register comprises numeral wheels 127 rotatable on shaft 128 in the supporting structure; they are visible through apertures 129 in the machine cover 4. Each numeral wheel 127 has a gear 130 adapted to be located by a detent 131 rockable on shaft 132 and biased by a spring 133 housed in a spring bar 134. Each numeral wheel 127 has a one-tooth pinion 135 co-acting with a customary rocker 136 pivoted on shaft 137. Gears 130 mesh with idler gears 138 rotatable on rod 132 adjacent to rockers 136, and also with idler gears 139 on shaft 140. Gears 139 are driven by a driver 141 slideable along a flat shaft 142 journalled in the supporting structure. Driver 141 is held between the left-hand carriage plate 7 and a bracket 143 secured hereto. As the carriage 9 is stepped transversely of the machine, driver 141 is also shifted along its shaft 142 into alignment with the respective gear 139. Gear 139 reserved for the D numeral wheel 127 meshes with a gear 144, Fig. 13, fixed to the pence numeral wheel 127 on the left thereof. Gear 139 reserved for D/8 is fixed to another gear 145 meshing with gear 130 on D/8 numeral wheel 127. Rocker 136 co-acting with S10 numeral wheel 127 is fixed by means of a bar 146 to the rocker 136 coacting with the S10 numeral wheel 127; thus, the carry from the S10 wheel as well as from the -1 numeral wheel 127 is effected into the 0 numeral wheel. One numeral wheel 127 with gears 130, 138, 139 is provided for each possible shift of the carriage, as indicated by references -4 to +7 and 10/- to D/8 adjacent to apertures 129 (Figure 18). It may be pointed out that in Figure 18 the shillings positions of the carriage are indicated by "S" above the respective apertures 129 and "10/-" or "1/-" below the respective aperture, while throughout the specification these positions are referred to as "S10" and "S1," respectively.

Fixed to shaft 142 is a gear 147 (Figure 9) meshing with an idler gear 148 journalled in the side frame 2; this idler 148 meshes with a gear 149 fixed to a carry shaft 150 journalled in the frame structure 2, 3, and driven in a manner to be described hereafter. Carry shaft 150 has the usual spring-loaded rocking pins 151 and restoring cams 152 co-operating in the well-known

manner with rockers 136 for the purpose of the carry operation. Briefly, in order to effect a carry the one-tooth pinion on numeral wheel 127 pushes the associated rocker 136 anti-clockwise around its pivot 137; the rear end of rocker 136 is so sloped as to cause the associated pin 151 to swing out sideways and to drive the idler 138 of the next higher denomination one step, thus effecting the carry. Rocking pin 151 is then restored by its spring (not shown), and the rocker 136 is restored by its associated cam 152 on shaft 150.

The revolution register is cleared in the same manner as the result register, by means of a comb-bar 153 and a clearing handle 154 (Figure 18).

Driving and Operating Means

The machine is operated by means of a handle 155 and crank 159 journalled in a bearing 157 (Figure 16) in the right-hand side frame 3. Gear 158 fixed to crank 159 meshes with gear 159 fast on shaft 160 which carries the cams 72, 78 and is journalled in the supporting structure 2, 3. Handle 155 is rotated in one direction only (clockwise) both for positive and negative operations. A suitably shaped spring-loaded pawl (not shown) is arranged to co-operate with gear 158 in order to prevent a rotation in the wrong (anti-clockwise) direction.

Gear 158 further meshes with a double gear 161 (Figure 16) journalled in side frame 3. This double gear 161 meshes with a clutch gear 162 rotatable on sleeve 163 on the flat carry shaft 150. Gear 161 further meshes with an idler gear 164 journalled in frame 3 and meshing with another clutch gear 165 rotatable on sleeve 166 on shaft 150. Thus, when the handle 155 is rotated, clutch gears 162, 165 rotate in opposite directions. Slidably mounted on shaft 150 between the gears 162, 165 is a dog clutch 167 which can be shifted by a clutch fork 168 pivoted at 169 in a bracket 170 into engagement either with gear 165 (for "positive" drive of carry shaft 150) or with gear 162 (for "negative" drive). For this purpose the upper end of clutch fork 168 carries a roller 171 co-acting with a double cam 172 fixed to shaft 173 journalled in the frame structure 2, 3. Also fixed to shaft 173 are two internal cams 174 (see also Figure 9A) adapted to co-operate with rollers 175 on plates 97 which support shafts 96, 99 of idlers 95, 98 of the products register. Fixed to shaft 173 is a handle 176 (Figures 17 and 18) which can be set to any one of three positions designated "X+", "−", and "÷". When the handle 176 is set to position "X+", the machine is conditioned for multiplication and addition; clutch 167 is in the position shown in Figure 16, cams 174 and idlers 95, 98 are in the position shown in Figures 9A. Consequently, the entries into the products register and into the revolution register are positive, numeral wheels 104 and 127 being driven anti-clockwise as viewed in Figure 9A and 9.

When the handle 176 is set to the position "−" the machine is conditioned for subtraction such as occurs during multiplication when using the method of "short-cutting." In this position of handle 176, cams 174 rock idlers 95, 98 so that both idlers are included in the gear-trains driving the numeral wheels 104, thus reversing their direction. Clutch 167 is shifted into engagement with clutch gear 162, thus reversing the rotation of carry shaft 150 and driver shaft 142. Consequently, the entries into both registers are made negative.

When the handle 176 is set to the "÷" position, the machine is conditioned for division. Cam 172, when in this position, causes clutch 167 to return into engagement with clutch gear 165; cams 174 are so shaped that they retain both idlers 95, 98 in working positions. Consequently, the entries into the products register are made negative, while the entries into the revolution register are made positive.

Various devices are incorporated in the machine in order to ensure its correct operation. However, as these devices are not necessary for a proper understanding of the invention, they have not been described herein and are not shown in the drawings. Other well-known devices such as additional registers, printing devices, and so forth may be incorporated in the machine without departing from the spirit of the present invention.

20

Operation

An example of a simple multiplication has been already given in connection with Figures 7, 8.

Assuming now it is desired to multiply £40,010: 0: 4d. by 19.9, it is usual to multiply by 20 and to subtract the product by 0.1, according to the "short-cutting" method. The multiplicand £40,010: 0: 3d is set up by means of setting levers 5 as already described, and the machine is conditioned for additive multiplication by setting the control handle 176 to "X+." Carriage 9 is then shifted to position +1 by depressing the shift knob 35, and the operating handle 155 is turned twice. The amount £400,100: 2: 6d. will be picked up by feelers 60 during each revolution of handle 155 and cam shaft 160 and entered into the products register positively through gear sectors 62, pinions 88, driving springs 94, gears 92, idlers 95, and gears 101; numeral wheels 104 will then show the double amount, namely £800,200: 5: 0d., the carry from the D wheel to the S1 wheel being effected as described above. The revolution register has been driven through gears 158, 161, 164, 165, clutch 167, carry shaft 150, gears 149, 148, 147, shaft 142, and driver 141; after the second revolution of handle 155 the revolution register will show "20." The carriage is then shifted to position -1 by turning the hand wheel 54, the control handle 176 is set to "−" and the operating handle 155 is turned once. The amount £4,001: 0: 0.3d. will be picked up by feelers 60 and entered into the products register negatively through gear sectors 62, pinions 88, springs 94, gears 92, idlers 95, 98, and gears 101; numeral wheels 104 will then show the result of the calculation as £796,199: 4: 11.7d., the carry being effected in the same manner as before but negatively, due to the reversal of wheels 104. Carry shaft 150 has been driven during the negative revolution through gears 158, 161, 162, and clutch 167, and the driver 141 has entered "1" negatively into the -1 numeral wheel 127, thus turning it from "0" to "9" and effecting the carry to the "0" numeral wheel 127 and turning it to "9." Consequently, the "0" numeral wheel 127 has effected a carry to the +1 wheel, turning it to "1." Thus, on completion of the negative revolution the revolution register shows the multiplier, viz. 19.9.

Assuming now it is desired to divide £894: 12: 1d. by £38: 17: 11d. Control handle 176 being set to "X+" and the carriage being in the initial position, the dividend £894: 12: 1d. is set up by means of setting levers 5 and is transferred to 75 the products register by a single revolution of

handle 155. Now, the revolution register is cleared by turning the handle 154, setting levers 5 are re-set according to the divisor £38: 17: 11d., and the control handle 176 set to "÷." As the dividend is obviously greater than nine times the divisor, the carriage is shifted to the +1 position and the operating handle 155 is rotated. In the course of the first revolution the amount £38: 17: 11d. $\times 10 = £388: 19: 2d.$ is negatively entered into the products register (through gear sectors 60, pinions 88, gears 92, idlers 95, 98) and thus subtracted from the dividend already in the register, which will then show £505: 12: 11d. During the second revolution the figure £388: 19: 2d. is again subtracted, and the products register will show £116: 13: 9d. Seeing that "11" is less than "38," the carriage is shifted to the initial position "0" and the handle 155 is again rotated. In this position of the carriage each revolution subtracts the divisor £38: 17: 11d. from the registered amount, and it will be found that after three revolutions the products register will show zero. The revolution register has been driven positively through gears 158, 161, 164, 165, clutch 167, shaft 159, gears 149, 148, 137, shaft 142 and the driver 141, namely the "+1" numeral wheel 127 two steps and the "0" numeral wheel three steps. Consequently, the revolution register now shows the quotient "23."

To take an example of a percentage calculation, supposing it is desired to add 3% to £175: 17: 11d., this amount is set up and, control handle 176 being on "X+" and the carriage being in the initial position, the operating handle 155 is turned once; the products register then shows £175: 17: 11d. and the revolution register shows "1." The carriage is then shifted to the -2 position and the handle 155 turned three times, thus adding the amount £175: 17: 11d. $\times 0.03 = £5: 5: 6.45d.$ to the products register, which thus will show the result £181: 3: 5.45d., and the revolution register will show "1.03."

Percentage method may be used to divide sterling amounts by decimal amounts. For instance, assuming it is desired to divide £97: 4: 9.5d. by 25, obviously $\frac{1}{25} = \frac{4}{100} = 4\%$; consequently £97: 4: 9.5d. is set up and the carriage is shifted to -2 position; control handle 176 being on "X+," operating handle 155 is turned four times. The products register then shows the quotient £3: 17: 9.5d. and the revolution register shows "0.04" which is the reciprocal value of the divisor 25.

It is evident that decimal calculations may be carried out in the pounds section of the machine in the usual way.

In order to illustrate the multiplication of a decimal amount by a sterling amount, a calculation $765 \times 1\frac{1}{4}d.$ is effected by aligning setting levers 5 designated L10², L10, and L1 with numerals 7, 6, 5, respectively, and the carriage is shifted into position D/8. On rotating the main handle 155 twice (since $\frac{1}{4}d. = \frac{2}{8}d.$), the amount 15: 11.25d. is entered into the products register as already described. The revolution register shows "1/4d." as the D/8 numeral wheel 127 has been stepped twice by driver 141 and gears 139, 145, 130. The carriage is now shifted to the D position, and the handle is turned once more to add to the products register £3: 3: 9d. = $765 \times 1\frac{1}{4}d.$ The products register now shows the result as £3: 19: 8.25d., and the revolution register shows 1 $\frac{1}{4}d.$

Division of sterling amounts by decimal amounts may be effected by utilising the non-

decimal carriage positions. To divide £98: 4: 10d. by 4, the dividend is set up and entered into the products register as described, whereupon the divisor 4 is set up and the carriage is shifted to the +1 position, since obviously 9 is greater than 4. After clearing the revolution register and setting the control handle 176 to "÷," the handle 155 is turned twice, until the significant numeral wheel L10 of the products register shows a remainder 1 which is smaller than the divisor 4. The revolution register now shows "20." The carriage is shifted into the 0 position, and the handle again rotated until the units wheel 104 shows a remainder 2 smaller than the divisor; the whole remainder being £2: 4: 10d. Revolution register now indicates "24." The carriage is shifted to the S10 position; each revolution of the handle now subtracts from the divisor $4 \times 10^2 = £2$, so that the pounds figure will disappear after the first revolution, which has transformed the indication of the revolution register to 24: 10.0.0d. The remainder now is 4: 10d., and on shifting the carriage to the S1 position it will be found that after a single revolution the shillings figure has disappeared, since $4 \times 1/- = 4/-$. The revolution register now shows 24: 11: 0.0d., and the products register shows 10d. On shifting the carriage into the D position and turning the handle twice, the remainder 2d. is reached; the revolution register shows 24: 11: 2.0d. The calculation is completed by shifting the carriage into the position D/8 and turning the handle four times; the products register now is clear, and the revolution register shows the quotient £24: 11: 2 $\frac{1}{2}$ d.

Without departing from the spirit of the present invention, the machine described above may be modified in many ways. Instead of being driven by hand it may be arranged to be driven by a motor. Setting levers 5 may be replaced by a suitable key-board arrangement. Manual operation of the machine may be replaced by an automatic device controlled by records sensed mechanically, electrically, or by means of light, for example as described in the specification to my prior British Patent No. 521,871. Instead of being shiftable together with the conversion mechanism, the set-up mechanism may be made stationary. The conversion mechanism may be arranged in a fixed position, and the feeler mechanism and/or the result register may be made shiftable. Further possible modifications will be apparent to those skilled in the art.

In the accompanying claims, the term "first factor" is intended to include all values to be entered into the products register, such as multiplicands, dividends, divisors, and so forth, whilst the term "second factor" relates to values registered in the revolution register, such as multipliers and quotients.

"Interrelated sets of units" relate to various denominations of the non-uniform factor; for instance, in the sterling notation the highest or pounds set of units comprises the units, tens, 65 and so forth of pounds; the shillings set of units comprises the units and tens of shillings; the pence set of unit comprises the pence, and the fractions set of units comprises fractions of a penny. It may be noted that the highest set of units, such as pounds sterling, is in the decimal notation. "Digital value" in a non-uniform notation is the equivalent of "digit" in decimal notation; it relates to all values 0-11 of pence, 0 and 10/- of the tens of shillings, fractions 0 to $\frac{1}{8}$ of the 70 eighths-of-penny denomination, but it may also

relate to digits 0-9 of pounds, or of units of shillings, or of decimal fractions of a penny. "Unit value" of a non-decimal denomination relates to the lowest digital value except 0; for instance, to 10/-, 1/-, 1d., and 1/8d. (or another predetermined fraction of a penny).

What I claim is:

1. In a calculating machine for non-uniform first factors comprising interrelated sets of units, the highest set of units being in the decimal notation, and for decimal second factors, and conversely for decimal first factors and non-uniform second factors, a products register, a sensing mechanism operatively associated with the said register, and means for operating the said sensing mechanism, in combination, a conversion mechanism comprising a plurality of groups of members, each group being associated with a denomination of a non-uniform first factor and each member within a group being associated with a digital value of the respective denomination, each of said members associated with the highest set of units comprising representations of the respective digit, of products formed by multiplying the respective digit by $1/10$, $1/100$, and so forth, and of products formed by multiplying the respective digit by the unit value of each non-decimal denomination of a non-uniform second factor, whilst each of said members associated with a lower set of units comprises only representations of products formed by multiplying the respective digital value by the digit 1 of each denomination of a decimal second factor, all said products being expressed in the interrelated sets of units, a first set-up mechanism for operatively associating with the said sensing mechanism those members which are associated with digital values and denominations of the first factor, and a second set-up mechanism for operatively associating with the said sensing mechanism those representations which correspond to the denominations of the second factor.

2. In a calculating machine according to claim 1, a carriage on which the said conversion mechanism is mounted, the said second set-up mechanism comprising means for displacing the carriage from an initial position associated with the units denomination of a decimal second factor into a first plurality of positions each associated with another denomination of a decimal second factor and into a second plurality of positions each associated with a denomination of the non-decimal sets of units of a non-uniform second factor.

3. In a calculating machine according to claim 1, a carriage on which the said conversion mechanism is mounted, the said second set-up mechanism comprising means for displacing the carriage from an initial position associated with the units denomination of a decimal second factor into a first plurality of positions each associated with another denomination of a decimal second factor and into a second plurality of positions each associated with a denomination of a non-decimal set of units of a non-uniform second factor, means for rendering inoperative the representations of the said respective digit and of said products formed by multiplying the respective digit by $1/10$, $1/100$ and so forth when the said carriage is positioned within the said second plurality of positions, and means for rendering inoperative the representations of the said products formed by

multiplying the respective digital value by the digit 1 of each denomination of a decimal second factor when the said carriage is positioned within the said first plurality of positions.

- 5 4. In a calculating machine of the type described, a revolution register comprising a plurality of denominational registering elements arranged co-axially in two groups, the first group comprising decimal registering elements each reserved for a denomination of a decimal second factor, and the second group comprising registering elements each reserved for a denomination of the non-decimal sets of units of a non-uniform second factor, a carriage shiftable transversely 10 of said register into a plurality of positions each associated with one of said registering elements, a shaft extending parallel to the axis of said register, means for rotating this shaft once during each calculating operation, and a driving element 15 slidable on said shaft in conformity with the positioning of the carriage and rotatable with the said shaft, the said driving element being adapted in each position of the carriage to turn the respective registering element one step during 20 each revolution of said shaft.
5. In a calculating machine of the type described, a products register, a set-up mechanism for the first factor in the Sterling notation, and a conversion mechanism comprising a plurality of 25 groups of members, each group being associated with a denomination of the Sterling first factor and each member within a group being associated with a digital value of the respective denomination, each of said members associated with a 30 pounds denomination comprising representations of products formed by multiplying the respective digit by 1, $1/10$, $1/100$ and so forth and also by ten shillings, one shilling, one penny, and a predetermined fraction of a penny, whilst each of 35 said members associated with the shillings, pence, or fractions of a penny comprises only representations formed by multiplying the respective digital value by the digit 1 of each denomination of a decimal second factor, all said products being 40 expressed in the interrelated sets of units, the said representations being arranged on each of said members in two parallel lines, one line comprising representations of pounds, units of shillings, pence, and fractions-of-penny components of the 45 said products, and the other line comprising representations of tens of shillings components of the 50 said products, and the other line comprising representations of tens of shillings components of the said products.
